US00D967146S

(12) **United States Design Patent** (10) **Patent No.:** **US D967,146 S**
Pacione et al. (45) **Date of Patent:** **** Oct. 18, 2022**

(54) **DISPLAY SCREEN OR PORTION THEREOF WITH GRAPHICAL USER INTERFACE**

(71) Applicant: **BioReference Health, LLC**, Elmwood Park, NJ (US)

(72) Inventors: **Vincent Pacione**, Elmwood Park, NJ (US); **Ryan Wiaranowski**, Elmwood Park, NJ (US); **Alexa Katz**, New York, NY (US); **Daniel Nosonowitz**, New York, NY (US); **Jin Sang Yoon**, New York, NY (US); **Riley Walker**, New York, NY (US); **Xuecheng Xu**, New York, NY (US)

(73) Assignee: **BioReference Health, LLC**, Elmwood Park, NJ (US)

(**) Term: **15 Years**

(21) Appl. No.: **29/812,564**

(22) Filed: **Oct. 22, 2021**

(51) LOC (13) Cl. **14-04**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.

1 Claim, 2 Drawing Sheets
